DISPENSARY RACK

Russell J. Wolfe, 2095 E. Oakfield Road,
Grand Island, N.Y. 14072

Filed May 12, 1967, Ser. No. 7,084

Term of patent 14 years

(Cl. D83—1)

Fig. 2.

Fig. 1.

Fig. 4.

Fig. 3.

Fig. 5.

Fig. 6.

Fig. 7.

FIG. 1 is a front elevational view of a dispensary rack showing my new design.

FIG. 2 is a top plan view thereof.

FIG. 3 is a bottom plan view thereof.

FIG. 4 is a view taken from the right side of FIG. 1; the opposite side view being substantially the same.

FIG. 5 is a rear elevational view thereof.

FIG. 6 is a vertical central sectional view thereof, taken on line 6-6, FIG. 5.

FIG. 7 is a horizontal sectional view thereof, taken on line 7-7, FIG. 5.

I claim:

The ornamental design for a dispensary rack, substantially as shown and described.
